UNITED STATES PATENT OFFICE

90,812

DESIGN FOR A GARMENT

Robert M. Lippmann, New York, N. Y.

Application June 28, 1933. Serial No. 48,578

Term of patent 3½ years

To all whom it may concern:

Be it known that I, ROBERT M. LIPPMANN, a citizen of the United States, and a resident of New York, New York county, State of New York, have invented a new, original, and ornamental Design for a Garment, of which the following is a specification, reference being had to the accompanying drawing, forming part thereof.

Fig. 1 in the drawing shows a front view of the garment with the collar turned down and Fig. 2 a rear view with the collar turned up; the sleeve at the left of the rear view being broken away for lack of room on the sheet of the drawing.

I claim:

The ornamental design for a garment substantially as shown and described.

ROBERT M. LIPPMANN.
